[57] CLAIM

The ornamental design for a combined liquid container and rotatable spout, substantially as shown and described.

DESCRIPTION

FIG. 1 is a perspective view of a combined liquid container and rotatable spout showing my new design;

FIG. 2 is a side elevational view, the opposite side being substantially a mirror image thereof;

FIG. 3 is a top plan view;

FIG. 4 is a bottom plan view;

FIG. 5 is a view looking from the left side of FIG. 2; and

FIG. 6 is a view looking from the right side of FIG. 2.
